FORM HANDLING MEANS FOR BUSINESS MACHINES

Fred Becker, Queens Village, N. Y., assignor to Underwood Corporation, New York, N. Y., a corporation of Delaware

Application October 27, 1955, Serial No. 543,111

7 Claims. (Cl. 197—136)

This invention relates to business machines, especially to those adapted for printing or typing upon a work sheet carried by a cylindrical platen and more particularly relates to an improved means for facilitating the introduction of short forms or work sheets into such machines.

Business machines such as typewriters, accounting machines and the like are generally provided with a cylindrical platen which is rotated to feed the work sheets from the rear up past a typing point located along the front of the platen. Some such machines are arranged to have the work sheets inserted from the front of the platen rather than from the rear but this generally calls for a more complicated and costly construction. The type of work to be performed by the machine dictates whether a rear-feed or front-feed arrangement is the most desirable.

At times it is desired to use business machines, particularly typewriters, for filling out comparatively short forms such as index or file cards and machines have been devised wherein such forms may be inserted at the front of the platen and the platen then rotated in the direction opposite to line-space direction to bring the form to position for typing the first line. Such machines employ a device for attaching the lower edge of the form to the platen and have means for limiting the rotation of the platen so that it may conveniently be oscillated between a position for inserting the form and position for typing the first line. One such arrangement of this type is shown in the patent to Carpenter, No. 2,239,643.

It is an object of the present invention to provide a business machine having an improved arrangement for facilitating the handling of relatively short forms.

It is a further object of the invention to provide a business machine which may be converted quickly and with a minimum of effort from one adapted for the usual type of work to one especially adapted for handling short forms.

It is a still further object of the invention to provide a platen assembly for use with a business machine which will greatly facilitate the handling of short forms.

These and other objects, features and advantages of the invention will become more readily apparent as the description of a preferred embodiment thereof proceeds.

Referring now to the drawing:

Figure 1 is a perspective view showing the platen and a portion of the paper carriage of a typewriter embodying the invention.

Figure 2 is an end view of the platen and carriage, partially in section and partially broken away to show some of the operating parts and showing the platen in work-sheet-inserting position.

Figure 3 is an end view showing a portion of the mechanism shown in Figure 2 and showing the platen in the first-line-of-typing position.

Figure 4 is a view partially in front elevation and partially in section showing one end of the platen and showing a spring means for rotating the platen to first-line-of-typing position.

2

Figure 5 is a sectional view taken along the line 5—5 of Figure 4, and

Figure 6 is a perspective view of a conventional platen assembly which may be substituted for the platen assembly of the present invention when it is desired to use the machine for purposes other than typing on short forms.

While the invention has been illustrated as applied to a typewriting machine it will be understood that it is not limited to that application but that in general it is adaptable to any business machine having a cylindrical platen. Since the details of construction of the platen carriage are not of the essence of the present invention, said carriage has been illustrated more or less diagrammatically as comprising a pair of end plates 10 and 11 mounted upon a grooved bar 12 and further tied together by various cross members, one of which is shown at 13. As shown in the patent to Helmond, No. 2,172,008, the end plates are provided with upwardly directed open ended bearing slots within which platen shaft bearings are rotatably and removably mounted. The grooved bar 12 is mounted upon roller bearings within a complementarily grooved member 14 forming a part of the base portion of the machine, thus mounting the carriage for letter-feed and return movement past a typing position.

The platen assembly of the present invention comprises a cylindrical platen 15 extending axially from the ends of which and fixed thereto are a pair of bearing shafts 16 (Figure 3) and 17 (Figure 4). When the platen assembly is in use, the bearing shafts 16 and 17 are rotatably mounted in the open ended bearing slots of the end plates 10 and 11 respectively. The platen is provided with any suitable means whereby the bottom edge of a work sheet or card 18 may be secured thereto. Such means is herein illustrated as a channel member 19 embedded in the surface of the platen and the card is held in position by being wedged beneath one of the inturned sides of said member.

For facilitating the rotative adjustment of the platen by either hand of the operator, knobs 20 and 21 are fixed to the bearing shafts 16 and 17 respectively. The knob 20 is formed at one end of a sleeve 22 the other end of which is flanged and has secured thereto a plurality of segments 23, see Figure 2, which slidably guide elements 24 of a clutch. The elements 24 are urged by a spring 25 toward an inactive position but are normally held in active position by a spring pressed ball 26. Rotatable on the shaft 16, or on the flange of the sleeve 22 as may be desired, is a ratchet wheel 27 having ratchet teeth 28 around its outside and closely spaced clutch teeth 29 around its inside. The clutch elements 24 normally engage the clutch teeth 29 to hold the ratchet wheel 27 fast with bearing shaft 16 and the platen. By pressing a button 30 toward the knob 20, the ball 26 may be moved away from the elements 24, whereupon the spring 25 moves said elements out of engagement with the clutch teeth 29 and the platen and ratchet wheel may be rotated independently of one another. While a particular form of clutch has been described, the structural details of the clutch are not of the essence of this invention and any form of clutch known in the business machine art as a variable line-space clutch may be employed.

For preventing accidental rotation of the platen and for holding the ratchet wheel 27 when it is desired to adjust the rotary position of the platen with respect to said ratchet wheel, a detent member 31 is pivotally mounted upon the carriage below the ratchet wheel. The detent member is urged by a compression spring 32 to normally engage a roller 33 carried on one arm thereof with the teeth 28 of the ratchet wheel. The detent member 31 is provided with an operating arm 34 adapted to be engaged by the lower end of a detent release lever 35

pivotedly mounted upon the carriage end plate 10. When it is desired to have the platen rotate freely without disturbing the angular adjustment of the platen with respect to the ratchet wheel, the detent may be released by moving the upper end of the detent release lever 35 rearwardly, as indicated in Figure 3.

It will be understood that the platen is line-spaced by moving the ratchet wheel 27 in a counterclockwise direction as viewed in the drawing. While any of various known means may be employed for turning the ratchet wheel, one suitable means is described in the patent to Helmond, No. 2,262,676 and a portion of such means is indicated in the drawing at 36.

At the right hand end of the platen, a flanged sleeve 37 surrounds the bearing shaft 17. The sleeve 37 is fixed to the platen and so of course is fixed with respect to the shaft 17 since, as previously mentioned, said shaft is fixed to the platen. Fastened around the sleeve 37 by means of a set screw 38 is a collar 39 to which the inner end of a coil spring 40 is pinned. At its outer end the spring 40 is secured to the flange of a cup member 41 and said cup member is connected by a strap 42 to an arm 43 secured to an anchor member 44 swingably mounted upon the bearing shaft 17. The spring 40 is so wound as to urge the platen in a clockwise direction as viewed in the drawing and to urge the anchor member 44 in a counterclockwise direction. When the platen assembly is in position in the carriage, the lower end of the anchor member 44 abuts the cross member 13 to thereby prevent counterclockwise movement of said anchor member and the energy of the spring 40 is thus directed toward urging the platen in a clockwise direction which is the direction opposite to the line spacing direction. However, for a reason hereinafter to be explained, the tension of the spring 40 is not sufficient to overcome the action of the detent 31.

A thumb screw 45 is screwed into the anchor member arm 43 and may be tightened against the surface of the platen to thereby lock the anchor member 44 to the platen so that when the platen assembly is removed from the carriage the spring 40 will be maintained under tension. For preventing accidental displacement of the thumb screw, a spring 46 may be provided between the head of said screw and the arm 43 to hold the set screw in whatever position to which it is turned.

Rotatably adjustable on the bearing shaft 17 is a collar 47 which may be locked to said shaft in any desired angular position by means of an elongated set screw 48. A stop member 49 secured to the carriage end plate cover 50, or to any other convenient part of the carriage, cooperates with the elongated set screw 48 to prevent line space movement of the platen beyond what is herein termed the work-sheet-inserting position. The work-sheet-inserting position of the platen is shown in Figures 1 and 2 and is the rotated position of the platen wherein the channel member 19 is conveniently accessible for receiving the bottom edge of the work sheet.

For preventing retrograde rotation of the platen beyond position for typing the first line on the work sheet, a stop member 51 is secured to the ratchet wheel 27 and said stop member cooperates with a fixed stop 52 forming a part of the framework of the carriage. This first-line-of-typing position of the platen is shown in Figure 3. By releasing the variable line space clutch and manually turning the platen, the relationship between the work sheet holding means 19 and the stop member 51 may be so adjusted that when the line space clutch is reengaged and the platen turned to bring the stop member 51 into engagement with the fixed stop 52 the work sheet, which is held at its bottom edge by the holding means 19, will be properly positioned for receiving the first line of typing.

In operation, the platen is turned by the line spacing mechanism or by rotating one of the knobs 20 or 21

until the set screw 48 contacts the stop 49, thus positioning the work sheet holding means 19 so that the bottom edge of the work sheet or card 18 may conveniently be attached to the platen. It has previously been mentioned that the ratchet wheel 27 is normally clutched to the platen and that the spring 40, while tending to rotate the platen in the direction opposite to its line spacing movement, is not sufficiently strong to move the platen against the action of the detent roller 33. Therefore, after attaching the work sheet to the platen, the operator pushes the detent release lever 35 rearwardly to free the ratchet wheel and platen from the action of the detent roller 33, whereupon the spring 40 snaps the platen and the ratchet wheel 27 in the direction opposite to line spacing to the position where the stop member 51 contacts the fixed stop 52, thus bringing the work sheet to position for receiving the first line of typing. The detent release lever 35 is then restored to normal position and typing and line spacing proceeds in the usual manner, the detent roller 33 serving to prevent undesired rotation of the platen by the spring 40. By proper adjustment of the angular relationship between the stop member 51 and the work sheet holding means 19 any desired first-line-of-typing position of the work sheet may be accurately determined.

When it is desired to use the machine for the more usual type of work, the thumb screw 45 is screwed down against the platen to prevent the unwinding of the spring 40 and the platen assembly is lifted out of the carriage.

An ordinary platen assembly such as indicated generally at 53 in Figure 6 may then be quickly substituted.

Having thus described a preferred embodiment of the invention, what is claimed is:

1. For use with a machine of the class described, a cylindrical platen having bearing shafts extending axially from each end thereof, work sheet holding means on said platen, a line space ratchet wheel rotatably mounted coaxially with said platen, stop means on said ratchet wheel adapted to cooperate with a relatively fixed stop when said platen is in use, clutching means for preventing relative rotation of said ratchet wheel and said platen, said clutching means being releasable to permit rotative adjustment of said ratchet wheel with respect to said platen whereby the relationship between said stop means and said work sheet holding means may be varied, spring anchoring means rotatably mounted upon one of said bearing shafts and adapted to engage a relatively fixed portion of the machine, a coil spring fixed at one end to said spring anchoring means and secured at its other end relative to said platen, and releasable means for locking said spring anchoring means to said platen.

2. For use with a machine of the class described, a cylindrical platen having bearing shafts extending axially from each end thereof, work sheet holding means on said platen, a line space ratchet wheel rotatably mounted upon one of said bearing shafts, stop means on said ratchet wheel adapted to cooperate with a relatively fixed stop when said platen is in use, clutching means for preventing relative rotation of said ratchet wheel and said platen, said clutching means being releasable to permit rotative adjustment of said ratchet wheel with respect to said platen whereby the relationship between said stop means and said work sheet holding means may be varied, spring anchoring means rotatably mounted upon the other of said bearing shafts and adapted to engage a relatively fixed portion of the machine, a coil spring fixed at one end to said spring anchoring means and secured at its other end relative to said platen, and releasable means for locking said spring anchoring means to said platen.

3. For use with a machine of the class described, a cylindrical platen having bearing shafts extending axially from each end thereof, work sheet holding means on said platen, a line space ratchet wheel rotatably mounted upon a first one of said bearing shafts, stop means on said ratchet wheel adapted to cooperate with a relatively fixed

stop when said platen is in use, a clutch for gripping said ratchet wheel to said bearing shaft, said clutch permitting rotative adjustment of said ratchet wheel with respect to said platen whereby the relationship between said stop means and said work sheet holding means may be varied, spring anchoring means rotatably mounted upon the other of said bearing shafts and adapted to engage a relatively fixed portion of the machine, a coil spring fixed at one end to said spring anchoring means and secured at its other end relative to said platen, and releasable means for locking said spring anchoring means to said platen.

4. In a machine of the class described, a platen carriage comprising a framework including a pair of end plates, a cylindrical platen having bearing shafts fixed relative thereto and extending axially from each end thereof, said bearing shafts being rotatably mounted in said end plates, a line-space ratchet wheel rotatably mounted upon one of said bearing shafts, a normally engaged clutch gripping said ratchet wheel to said bearing shaft, said clutch permitting angular adjustment of said platen with respect to said ratchet wheel, cooperating stop members on said ratchet wheel and said carriage for preventing retrograde rotation of said platen beyond the desired first-line-of-typing position, adjustable stop means for variably limiting the extent of rotation of said platen in line-space direction, said last named means selectively defining the various work-sheet-inserting positions of said platen, spring means urging said platen to first-line-of-typing position, normally engaged spring urged detent means yieldingly restraining rotation of said ratchet wheel and said platen, and manually operable means for releasing said detent means to thereby free said ratchet wheel and said platen to the action of said spring means whereupon said spring means will rotate said platen to first-line-of-typing position.

5. In a machine of the class described, a reciprocatable carriage mounted for letter-feed and return movement across a typing position, said carriage comprising a pair of end plates having open-ended bearing slots therein, a cylindrical platen, work sheet holding means on said platen for securing the bottom edge of a work sheet to said platen, platen bearing shafts extending axially from the ends of said platen and fixed relative thereto, said bearing shafts being mounted in said open-ended bearing slots whereby said platen is rotatably and removably mounted in said carriage, an anchor member rotatably mounted on one of said bearing shafts, spring means fixed at one end relative to said platen and secured at its other end to said anchor member, cooperating means on said anchor member and said carriage for preventing movement of said anchor member by said spring means, said spring means being biased to rotate said platen in the direction opposite to line-space direction, a line-space ratchet wheel rotatably mounted upon one of said bearing shafts, a normally engaged clutch gripping said ratchet wheel to said bearing shaft, said clutch permitting angular adjustment of said platen with respect to said ratchet wheel, cooperating stop members on said ratchet wheel and said carriage for preventing retrograde rotation of said platen beyond the desired first-line-of-typing position, means for limiting the extent of rotation of said platen in line-space direction, said last named means defining the work-sheet-inserting position of said platen, normally engaged spring urged detent means yieldingly restraining rotation of said ratchet wheel and said platen, manually operable means for releasing said detent means to permit free rotation of said ratchet wheel and said platen between work-sheet-inserting position and first-line-of-typing position, said spring means serving to impart retrograde rotation to said platen to the extent defined by said cooperating stop members when said detent means is released but said spring means having insufficient strength to move said platen when said detent means is engaged, and means for locking said anchor member to said platen whereby said platen may be removed from the carriage without disturb-

ing the relationship between said platen and said anchor member.

6. In a machine of the class described, a reciprocatable carriage mounted for letter-feed and return movement across a typing position, said carriage comprising a pair of end plates having open-ended bearing slots therein, a cylindrical platen, work sheet holding means on said platen for securing the bottom edge of a work sheet to said platen, platen bearing shafts extending axially from the ends of said platen and fixed relative thereto, said bearing shafts being mounted in said open-ended bearing slots whereby said platen is rotatably and removably mounted in said carriage, an anchor member rotatably mounted on one of said bearing shafts, a coil spring having its inner end fixed to said platen and at its outer end connected to said anchor member with respect to which said platen may be rotated to a limited extent, said coil spring being so arranged as to store up energy when the platen is rotated in line-space direction relative to said anchor member, cooperating means on said anchor member and said carriage for preventing movement of said anchor member by said coil spring, a line-space ratchet wheel rotatably mounted upon one of said bearing shafts, a normally engaged clutch gripping said ratchet wheel to said bearing shaft, said clutch permitting angular adjustment of said platen with respect to said ratchet wheel, cooperating stop members on said ratchet wheel and said carriage for preventing retrograde rotation of said platen beyond the desired first-line-of-typing position, adjustable stop means for variably limiting the extent of rotation of said platen in line-space direction, said last named means selectively defining the various work-sheet-inserting positions of said platen, normally engaged spring urged detent means yieldingly restraining rotation of said ratchet wheel and said platen, and manually operable means for releasing said detent means to permit free rotation of said ratchet wheel and said platen between a work-sheet-inserting position and the first-line-of-typing position, said coil spring serving to impart retrograde rotation to said platen to the extent defined by said cooperating stop members when said detent means is released and said coil spring having insufficient strength to move said platen when said detent means is engaged.

7. In a machine of the class described, a reciprocatable carriage mounted for letter-feed and return movement across a typing position, said carriage comprising a pair of end plates having open-ended bearing slots therein, a cylindrical platen, work sheet holding means on said platen for securing the bottom edge of a work sheet to said platen, platen bearing shafts extending axially from the ends of said platen and fixed relative thereto, said bearing shafts being mounted in said open-ended bearing slots whereby said platen is rotatably and removably mounted in said carriage, an anchor member rotatably mounted on one of said bearing shafts, a coil spring having its inner end fixed to said platen and at its outer end connected to said anchor member with respect to which said platen may be rotated to a limited extent, said coil spring being so arranged as to store up energy when the platen is rotated in line-space direction relative to said anchor member, cooperating means on said anchor member and said carriage for preventing movement of said anchor member by said coil spring, a line-space ratchet wheel rotatably mounted upon one of said bearing shafts, a normally engaged clutch gripping said ratchet wheel to said bearing shaft, said clutch permitting angular adjustment of said platen with respect to said ratchet wheel, cooperating stop members on said ratchet wheel and said carriage for preventing retrograde rotation of said platen beyond the desired first-line-of-typing position, means for limiting the extent of rotation of said platen in line-space direction, said last named means defining the work-sheet-inserting position of said platen, normally engaged spring urged detent means yieldingly restraining rotation of said ratchet wheel and said platen, manually operable means

for releasing said detent means to permit free rotation of said ratchet wheel and said platen between work-sheet-inserting position and first-line-of-typing position, said coil spring serving to impart retrograde rotation to said platen to the extent defined by said cooperating stop members when said detent means is released but said coil spring having insufficient strength to move said platen when said detent means is engaged; and means for locking said

anchor member to said platen whereby said platen may be removed from the carriage without disturbing the angular relationship between said platen and said anchor member.
